UNITED STATES PATENT OFFICE.

SAMUEL HOUGH, OF ATCO, NEW JERSEY.

AUTOMATIC FEED FOR LATHES.

1,297,690.

Specification of Letters Patent. Patented Mar. 18, 1919.

Application filed March 25, 1918. Serial No. 224,587.

To all whom it may concern:

Be it known that I, SAMUEL HOUGH, a citizen of the United States, residing at Atco, in the county of Camden and State of New Jersey, have invented new and useful Improvements in Automatic Feed for Lathes, of which the following is a specification.

My invention relates to new and useful improvements in automatic feed for lathes, and has for its object to provide in a device of this character means whereby the power for driving the boring bar forward may be greatly increased particularly for use in boring steel billets such as used in the manufacture of shells or projectiles.

Another object of the invention is to provide a split feed nut of unique construction inclosed in a housing having means to open and close said feed nut, said housing being pivoted or journaled in a suitable bifurcated bracket whereby the rotation of the housing will open or close said feed nut.

A further object of the invention is to provide a split feed nut operating upon a boring bar, the former being opened and closed by the rotation of its housing and spring actuated means to quickly rotate the housing in one direction for opening said feed nut, said means being normally held in an inoperative position by a latch which is withdrawn from engagement with said means at a predetermined time by an adjustable dog on the feed bar.

A still further object of the invention is to provide a boring bar bearing in a device of this character which will eliminate all undue lateral movement and positively hold the boring bar in central alinement with the chuck, said bearing consisting of an integral rectangular bearing surface or section on the boring bar and a box in which said section slides snugly fitting said section.

With these ends in view, this invention consists in the details of construction and combination of elements hereinafter set forth and then specifically designated by the claims.

In order that those skilled in the art to which this invention appertains may understand how to make and use the same, I will describe its construction in detail referring by numerals to the accompanying drawings forming a part of this application, in which:

Figure 1, is a side elevation of my auto-

matic feed, portions thereof being broken away and shown in section to clearly illustrate the invention it being shown applied to a lathe, a part of which is illustrated. 60

Fig. 2, is a rear end view thereof removed from the lathe with parts broken away and shown in section to illustrate the construction, and

Fig. 3, is a section at the line 3—3 of 65 Fig. 1.

In carrying out my invention as here embodied 2 represents a lathe bed or the frame of a suitable machine to which my invention may be applied and said lathe bed carries 70 the ordinary and well known shears 3 with which registers the inverted V shaped grooves 4 in the under side of the base plates 5 and 6 which are adapted to be bolted to the bed plate in any ordinary and 75 well known manner.

The base plate 6 carries two pedestals 7 and 8 which may be of any desirable shape, size or configuration and at the upper ends of these pedestals are located the journal 80 boxes or bearings for the boring bar 9, the latter end of which also runs through the tail stock of the lathe while the forward end of said boring bar has an integral rectangular or square bearing surface or section 10 85 of a length slightly greater than the entire longitudinal movement of the boring bar and this rectangular bearing surface is slidably mounted in a suitable rectangular bearing or box located at the upper end of the 90 pedestal 11 carried by the base plate 5 and as the rectangular bearing section or surface 10 snugly fits its box, there can be no lateral movement of the boring bar, so that when centered with relation to the lathe 95 chuck the two must absolutely always remain in their relative centered positions thereby producing absolutely accurate work.

The rear portion of the boring bar is threaded as at 12 and coating therewith are 100 the two elements 13 and 14 of the split feed nut, each element of said feed nut having a pair of oppositely projecting lugs 15 which register with and work in the inclined or angular slots 16 formed in the feed nut 105 housing 17 which is provided with a chamber 18 of suitable configuration to pass over the threaded portion of the boring bar and inclose the two elements of the feed nut and said chamber is of sufficient size to permit 110 a certain amount of movement of the housing without interfering with the other co-

operating parts. The angular grooves or slots 16 project outwardly from the vertical center of the housing when said housing is in the position illustrated in Fig. 1.

- 5 With the housing is formed two oppositely and outwardly projected trunnions 19 which are pivoted or journaled in the arms 20 of the bifurcated bracket 21 so that said housing may be rotated within the limits of 10 the slots 16 and in order that said housing may be manually rotated, one of the trunnions projects through and beyond the outer surface of one of the arms of the bifurcated bracket a sufficient distance to permit a suitable handle 22 to be mounted thereon and in order that said housing may be rotated mechanically I form a projection 23 therewith which extends from its outer surface and its utility will be hereinafter described.
- 15 20 The bifurcated bracket 21 is carried by the worm gear 24 and at the end opposite said worm gear, said bracket is provided with a thrust head 25 against which the housing of the split feed nut may abut.

- 25 30 The worm gear and bracket are journaled between the two pedestals 7 and 8 in any well known and approved manner as by thrust bearings and said worm gear is driven by a worm 26 mounted upon a shaft 27 to which power and motion are transmitted by some suitable means such as a beveled gear 28 carried by one end of said shaft.

35 The pedestal 8 is provided with an integral spring housing 29 having one end closed as at 30 with a hole 31 therethrough while the other end of the housing is open and has mounted therein a cap 32 with a hole 33 therethrough in alignment with the hole 31. In these holes is slidably mounted 40 the rod 34, the inner end of which is beveled as at 35 so that when the projection 23 strikes this beveled end after the rod has been moved inward, the feed nut housing will be rotated in one direction to separate 45 the members of the feed nut whereby they will be disengaged from the threaded portion of the boring bar.

50 The rod 34 has a collar 36 or its equivalent located adjacent its inner end, said collar is located within the housing 29 and is engaged as the movable member by one end of the coiled spring 37 which is also located within the housing and is coiled about the rod and the opposite end of said spring engages 55 the cap 32 as the stationary member. This rod 34 also has a collar 38 or its equivalent located adjacent the outer end thereof and outside of the housing and is adapted to be engaged by the spring actuated latch 39 60 when the rod 34 is withdrawn against the action of the spring 37 which may be accomplished by means of a suitable hand hold 40 at the outer end of said rod.

65 The latch 39 is slidably mounted in a suitable barrel 41 preferably formed as an in-

tegral part of the housing 29 and in the bore of this barrel is located a spring 42 engaging a collar 43 or its equivalent carried by the latch as a movable member and also engaging the outer end wall of the barrel as 70 the stationary member so that the latch is normally forced toward the rod 34. The inner or lower end of the latch is rearwardly beveled as at 44 so that when the rod 34 is drawn outward, said latch will ride over 75 the collar 38 while the upper or outer end of said latch has an extension or finger 45 which lies in the path of travel of the adjustable dog 46 which is adjustably mounted upon the boring bar and is held in any suitable adjustment by any well known means such as a set screw or bolt 47.

The boring bar may be provided with a yoke 48 whereby suitable means may be connected with the boring bar or quickly sliding 85 the same back when desired or after an operation has been completed.

The end of the boring bar adjacent or toward the lathe chuck is provided with suitable means whereby a boring tool or 90 cutting head may be attached thereto and with the attachment, as here described, I prefer to use my improved adjustable cutting head 49 which carries a plurality of cutting tools and which is fully described in 95 my application, Serial Number 190,708, filed September 11, 1917, and when such a cutting head is used with this device, the plurality of tools after entering the work will also act as a bearing for the gradually extending end 100 of the boring bar which will prevent chattering and cause the work to be finished accurately which is highly essential in the manufacture of munition shells and projectiles.

105 When the work has been placed in the chuck ready to be bored or otherwise finished, the boring bar 9 is first moved back a sufficient distance to permit the insertion of the work after which the members 13 and 110 14 of the feed nut are closed upon the threaded portion 12 of the boring bar by rotating the housing 17 in the direction of the arrow A, Fig. 1 which will cause the ends of the grooves or slots 16 which are 115 the greatest distance from the longitudinal center of the boring bar to be moved away from the vertical center of the feed nut when constructed as shown in Fig. 1 thereby acting as cams upon the lugs 15 and thereby 120 force the members of the split nut toward the boring bar and into engagement with the threads thereof. The rod 34 may next be withdrawn or pulled outward against the action of the spring 37 so as to withdraw 125 the inner end of said rod out of the path of travel of the projection 23 and at the same time compress the spring. This action will cause the latch 39 to ride over the collar 38 and thereby in behind the same, thus holding 130

the rod 34 in a set position as shown in Fig. 1. The dog 46 is then adjusted to the proper position for the depth of bore desired in the work or the distance which it is desired that the boring bar shall travel.

The power then being applied from some suitable source through the beveled gear 28 will drive the worm 26 which will transmit power to the worm gear 24 and since the feed nut is carried by said worm gear or certain fixtures thereof an enormous driving power is directly applied to the boring bar. As will be obvious, the revolving of the worm gear 24 with the bracket 21, the housing 17 and the elements 13 and 14 of the feed nut will feed the boring bar toward the chuck or work holding device.

At some point through the forward feeding of the boring bar, the dog 46 will engage the finger 45 of the latch 39 and draw said latch outward against the action of its spring 42 thus disengaged the inner end of said latch from the collar 38 which will release the rod 34 and permit it to be quickly forced inward and by its spring 37 which will project the inner beveled end 35 of said rod into the path of travel of the projection 23 and as soon as said projection strikes the beveled inner end of the rod, it will be caused to ride on said beveled end and move in a direction opposite to the arrow A in Fig. 1 causing the housing 17 to rotate about its trunnions 19 so that the ends of the slots or grooves 16 farthest from the longitudinal center of the boring bar will be moved toward the vertical center of the feed nut when constructed as shown in Fig. 1 and this will force the members of the feed nut away from the boring bar so as to disengage said members from the threaded portion and stop the feeding of the boring bar.

Of course I do not wish to be limited to the exact details of construction as herein shown, as these may be varied within the limits of the appended claims without departing from the spirit of my invention.

Having thus fully described my invention what I claim as new and patentable is:—

1. An automatic feed comprising pedestals, a boring bar having a threaded portion, slidably mounted in said pedestals, a worm gear revolving about the boring bar, a bracket carried by the worm gear, a housing rotatably journaled in said bracket, said housing having angular or inclined slots, a split feed nut within the housing adapted to engage the threaded portion of the boring bar, lugs carried by the parts of the feed nut registering with the slots and means for rotating the housing to open or close the feed nut.

2. An automatic feed comprising pedestals, a boring bar having a threaded portion, slidably mounted in said pedestals, a worm gear revolving about the boring bar, a

bracket carried by the worm gear, a housing rotatably journaled in said bracket, said housing having angular or inclined slots, a split feed nut within the housing adapted to engage the threaded portion of the boring bar, lugs carried by the parts of the feed nut registering with the slots, means for rotating the housing in one direction to close the feed nut, a projection extending from the housing and spring actuated means adapted to be moved into the path of travel of the projection whereby the housing will be rotated in the opposite direction to open the feed nut. 70

3. An automatic feed comprising pedestals, a boring bar having a threaded portion, slidably mounted in said pedestals, a worm gear revolving about the boring bar, a bracket carried by the worm gear, a housing rotatably journaled in said bracket, said housing having angular or inclined slots, a split feed nut within the housing adapted to engage the threaded portion of the boring bar, lugs carried by the parts of the feed nut registering with the slots, means for rotating the housing in one direction to close the feed nut, a projection extending from the housing, a spring actuated means for normally holding the first named spring actuated means withdrawn or in a set position and an adjustable dog carried by the boring bar to operate the last named spring actuated means when the boring bar has traveled a predetermined distance. 80 85 90 95

4. An automatic feed comprising a threaded boring bar, a gear journaled to revolve about the boring bar, a bracket carried by the gear, a feed nut housing rotatably journaled in the bracket and revolving therewith, said housing having inclined slots and a two part feed nut coacting with the threaded portion of the boring bar, each part of said feed nut carrying means registering with the inclined slots whereby the rotation of the rotation of the housing will move the feed nut parts toward or away from the boring bar. 100 105 110

5. An automatic feed comprising a threaded boring bar, a two part feed nut coacting therewith, each part having lugs projecting therefrom, a housing in which the feed nut is mounted, said housing having means for engagement with the lugs whereby the rotation of the housing will open or close the feed nut and trunnions projecting from the housing for rotatably mounting the housing in a suitable supporting means. 115 120

6. An automatic feed comprising a threaded boring bar, a two part feed nut coacting therewith, each part having lugs projecting therefrom, a housing in which the feed nut is mounted, said housing having means for engagement with the lugs whereby the rotation of the housing will open or close the feed nut, trunnions projecting from the 125 130

housing, a bracket revolving about the boring bar in which the housing is rotatably journaled by means of its trunnions, means on one of the trunnions for rotating the housing in one direction and means for rotating it in the opposite direction.

7. In a boring bar feed, a boring bar, a split feed nut, a rotatable feed nut housing provided with means coacting with suitable means on the feed nut whereby the latter may be opened and closed, a projection on said feed nut housing, a spring housing open at one end and closed at the other, said closed end having a hole therethrough, a cap provided with a hole, mounted in the open end, a bar slidably mounted in said holes, the inner end of said bar being beveled and adapted to coact with the projection for rotating the feed nut housing in one direction, the outer end of said bar having a hand hold, a collar on the bar located within the spring housing, a spring engaging said col-

lar and the housing cap for normally projecting the inner end of the bar into the path of travel of the projection, another collar carried by the bar located outside of the spring housing, a barrel formed with the spring housing, a latch slidably mounted in said barrel and adapted to engage the last named collar for holding the bar withdrawn, a spring within the barrel for normally forcing the latch toward the bar, a finger on the latch and an adjustable dog on the boring bar adapted to engage the finger when the boring bar has traveled a predetermined distance to withdraw the latch from engagement with the bar and permit the action of the spring to force the bar into the path of travel of the projection on the housing.

In testimony whereof, I have hereunto affixed my signature.

SAMUEL HOUGH.
